CODED TRACK CIRCUIT RAILWAY SIGNALING SYSTEM

Philip H. Luft, Penn Township, Allegheny County, Pa., assignor to Westinghouse Air Brake Company, Wilmerding, Pa., a corporation of Pennsylvania

Application August 5, 1954, Serial No. 447,983

8 Claims. (Cl. 246—34)

My invention relates to coded railway signaling systems, and particularly to an improved arrangement for supplying coded energy in a coded railway signaling system for the control of cab signals and/or speed control equipment on vehicles traveling through a stretch of track equipped with apparatus embodying my invention.

In conventional coded railway signaling systems, energy coded at one or another of several different rates, say, for example, 180 or 75 times per minute, is supplied to the rails of a section of track at the exit end thereof, and flows over the section rails to apparatus located at the entrance end of the stretch, which apparatus is selectively responsive to the reception of impulses of energy at the various code rates to thereby control wayside signals or other traffic controlling devices. Continuous inductive cab signals or automatic speed control for vehicles which travel over the stretch may be provided by employing alternating current energy for the trackway codes, and providing suitable apparatus on the vehicles for detecting the presence of such codes in the track rails of the section over which the vehicle is traveling. Such cab signal apparatus is usually arranged so that the cab signal aspect repeats the aspect of the wayside signal previously passed by the train. That is, when a train passes a signal displaying a green or clear aspect, coded energy at a particular rate, say, for example, 180 times per minute, is being supplied to the rails of the section at the exit end thereof. The reception of code at the 180 code rate by the train-carried apparatus will cause the cab signal apparatus to display a green or clear aspect. If the train passes a signal displaying a yellow or approach aspect, the apparatus is usually arranged so that coded energy at the 75 code rate is supplied to the rails of the section in advance of the signal so that the cab signal apparatus will display a yellow or approach aspect in the cab of the vehicle. The presence of steady energy, the absence of energy, or the presence of energy at a frequency which is ineffective to operate the cab signal apparatus will each cause the cab signal to display a restrictive or caution aspect. It will accordingly be seen that when a train passes a wayside signal displaying an approach aspect with the signal in advance displaying a red or stop aspect, the cab signal apparatus will continue to display a yellow or approach aspect throughout the entire length of the section.

It is sometimes preferred to provide what is known in the railway signaling art as a code change point at an intermediate point in the track stretch between wayside signals so that energy coded at the 75 code rate may be supplied to the rails of the section from the code change point to the signal in the rear, but steady energy or no energy is supplied to the section in advance of the code change point, that is, the section between the code change point and the signal in advance. Such an arrangement is particularly useful for wayside signals which display an absolute stop aspect, requiring all trains to come to a stop and remain stopped as long as the signal displays its stop aspect. With such an arrangement, if the wayside

2

signal is displaying its stop aspect, the next signal in the rear will display its approach aspect. A train passing the next signal in the rear will receive 75 code energy, and accordingly an approach cab signal aspect will be displayed, until the train passes the code change point, at which time the cab signal will operate to display its restrictive or caution aspect, thus giving additional warning to the engineman that he is approaching an absolute stop signal. Under such circumstances, the apparatus

10 must be arranged so that, when the signal in question displays a clear or approach aspect, energy coded at the 180 code rate will be supplied to the rails of the section immediately in the rear of the signal, and will be cascaded at the code change point intermediate in the stretch, so that the section in the rear of the code change point is also supplied with energy coded at the 180 code rate.

However, when the signal in question is at stop, the apparatus must be arranged in such manner that energy at the 75 code rate will be supplied to the rearmost section 20 of track, that is, the section between the code change point and the next signal in the rear of the signal in question when a train is occupying this first section, and no energy will be supplied to the second section extending between the code change point and the signal in question when a train is occupying this second section.

Although a number of methods have been proposed in the past for providing such operation and providing suitable equipment for use with code change points, such apparatus usually has the disadvantage of requiring line 30 wire control circuits extending between the signal locations and the code change point location.

Accordingly, it is an object of my invention to provide an improved coded railway signaling system, arranged to provide a code change point location in a section of track extending between two wayside signal locations, with the apparatus arranged so as to require no line wires between either of the signal locations and the code change point location.

Another object of my invention is to provide an improved coded railway signaling system in which a code change point location is provided at an intermediate point between two wayside signals, the control of apparatus being provided by the use of feedback code energy supplied from the code change point location to the signal location in advance of a code change point, such feedback code energy being generated by a novel arrangement of apparatus which insures that the feedback code impulses will not interfere with the proper transmission of the master code impulses supplied from the signal location in advance, notwithstanding the fact that the master code energy must be coded at a plurality of different code frequencies in accordance with traffic conditions in advance of the section.

A further object of my invention is to provide a coded railway signaling system in which, at a code change point, feedback coded energy is supplied to the rails of the section extending between the code change point location and the next signal location in advance, such feedback code energy being generated by a novel arrangement of 55 relay circuits for generating impulses of reverse code energy having a specified time duration and occurring at a specified time during the code cycle, notwithstanding the frequency of the master code energy supplied to the code change point location from the signal location in advance.

Other objects of my invention and features of novelty thereof will become apparent from the following description taken in connection with the accompanying drawings.

I shall describe two preferred embodiments of my invention, and shall then point out the novelty in the claims.

In practicing my invention, I provide, in a coded rail-

way signaling system using trackway codes of alternating current having a given frequency for the control of cab signal equipment on trains which move through a section of track, apparatus which transmits reverse code impulses or feedback code impulses from the normal entrance end of the section to the normal exit end of the section. These impulses of reverse code energy are transmitted at a rate less than the frequency of traffic controlling code impulses supplied from the apparatus at the normal exit end of the section, and the reception of these reverse or feedback code impulses at the exit end of the section governs suitable means for controlling the supply of the master code impulses of track energy to the rails of the section at the exit end thereof.

The reverse code impulses are generated as the result of the recurrent operation of a first and a second impulse relay, which are arranged to govern each other to recurrently operate in a cyclic manner such that the first relay is recurrently picked up for a relatively short time interval, with the "off" intervals between the picked-up periods being substantially longer than the "on" or picked-up periods. This first impulse relay is employed to govern the supply of energy to the track rails at the normal entrance end of the track section.

When no master code energy is being received at the entrance end of the section, the two impulse relays operate recurrently at a rate determined by their parameters and the parameters of their controlling circuits. However, when impulses of master code energy are being received at the entrance end of the section, the first impulse relay is additionally governed by the code following track relay which is operated by the master code impulses, to thereby obtain proper synchronization of the master and reverse code impulses.

In the drawings, Figs. 1A and 1B, when placed side by side with Fig. 1B to the right of Fig. 1A, illustrate in a diagrammatic manner a stretch of railway track equipped with a signaling system embodying my invention, and

Fig. 2 is a fragmentary diagrammatic view of a modification of the apparatus shown in Fig. 1A.

Referring to Figs. 1A and 1B of the drawings, there is shown a stretch of railway track including track rails 3 and 5, extending between two wayside signal locations 2S and 4S, and divided into a first track section designated by the reference character 2T, a second track section designated by the reference character 2AT, and a third track section in advance of signal 4S designated by the reference character 4T by the usual insulated rail joints 7. The wayside signals 2S and 4S govern the movements of traffic through the sections in advance of the signals, signal 2S governing the movement of traffic into the stretch including sections 2T and 2AT, and signal 4S governing the movement of traffic into section 4T. The signals may be of any of the well-known types, and as here shown, are of the color light type of signal having a green lamp G which when lighted provides a clear aspect, a yellow lamp Y which when lighted provides an approach aspect, and a red lamp R which when lighted provides a stop aspect.

As indicated by the arrows on the drawings, traffic normally moves through the stretch of track including sections 2T, 2AT and 4T in the direction from left to right, and it is assumed that vehicles or trains moving through the section are equipped with cab signal or train control apparatus of the type well known in the art which responds to the presence of alternating current energy of a predetermined frequency supplied at different code rates to the section rails, through the medium of inductive pickup apparatus on the vehicle or train. A detailed description of the vehicle-carried apparatus is not included herein since this apparatus may be any one of a number of suitable types, and may be, for example, of the type shown and described in Letters Patent of the United States No. 2,462,454, issued to Leslie R. Allison on February 22, 75

1949, for Train-Carried Cab Signal Apparatus. It is deemed sufficient to point out that the apparatus on the vehicles or trains which move through the stretch of track is arranged so that alternating current energy having a frequency of 100 cycles and supplied to the rails of the section at the rate of 180 times per minute will cause the display of a clear aspect on the cab signal apparatus, whereas the presence of 100 cycle energy in the section rails coded at the 75 code rate will cause the display of an approach aspect on the cab signal apparatus, and the presence of steady energy having a 100 cycle carrier frequency, or the absence of any energy, or the presence of 100 cycle energy at code rates less than 75 impulses per minute will cause the apparatus to display a restrictive aspect in the cab of the vehicle or train. It is also to be pointed out that the vehicle-carried apparatus will not respond to any coded energy other than that having the 100 cycle carrier frequency.

The apparatus located at the first signal location, that is, the location of signal 2S, includes a code following track relay 2TR connected across the rails of section 2T through a 100 cycle filter, which filter is constructed and arranged in the usual manner so that only alternating current energy having a frequency of 100 cycles per second will be supplied therethrough to operate the relay 2TR. For detecting the code following operation of relay 2TR, there is provided a decoding transformer 2DT, which governs the operation of a signal control relay 2HR, and also governs a clear signal control relay 2DR through a decoding unit 180DU, the relays 2HR and 2DR governing the aspect displayed by the wayside signal 2S. At the code change point, located at a point intermediate in the stretch and at the point of adjacency of the track sections 2T and 2AT, there is provided a track transformer 2TT having a secondary winding connected across the section rails and having a primary winding supplied with energy by a circuit including a contact of the code following track relay 2ATR which is arranged to be connected at times to the rails of section 2AT through a 100 cycle filter, and a back contact repeater relay 2ABSA, which is governed by a back contact of the track relay 2ATR. The apparatus at the code change point location also includes a reverse code track transformer 2AITT which is energized in a manner to be subsequently described for supplying impulses of energy to the rails of section 2AT at the left-hand or entrance end thereof, under the control of a first impulse relay 2AIR, which in turn is governed in part by a second impulse relay 2AIM. The apparatus further includes a code following track relay repeater relay 2ATM, and a front contact repeater relay 2AFSA, plus a snubbing circuit including a capacitor Q1 and a resistor R1 for at times rendering relay 2AIR slightly slow in releasing.

At the second signal location, Fig. 1B, there is provided a track transformer 2ATT, arranged so that energy may be supplied at times through this transformer to the rails of section 2AT at the exit end thereof, an approach code following relay 4AR which is arranged to be connected at times across the rails of section 2AT through a 100 cycle filter, and a slow release code detecting approach repeater relay 4AM, which is arranged to be energized by code following operation of relay 4AR, utilizing a snubbing circuit comprising a capacitor Q2 and a resistor R2. The apparatus at the signal location 4S also includes a code transmitting relay 4CTM, which governs the supply of master code impulses to the rails of section 2AT at the exit end thereof, this code transmitting relay being supplied with impulses of energy from code transmitting devices designated by the reference character CT preceded by a number indicating the frequency of their operation, namely, 180CT and 75CT, which operate their contacts respectively at the rates of 180 and 75 times per minute. The selection of the code operating speed for the code transmitting relay 4CTM is provided by contacts of relays 4HR and 4DR, the controls of which are not shown, but which are governed by traffic conditions in advance of

signal 4S in any suitable manner, as, for example, in a manner similar to that shown for relays 2HR and 2DR associated with signal 2S. The contacts of relays 4HR and 4DR also govern the lighting circuits for signal 4S in a conventional manner.

Energy for the operation of various of the relays is furnished by a suitable source of low voltage direct current, not shown, and having positive and negative terminals designated by the reference characters B and N, respectively. It is to be understood that such a source is provided at each of the three locations shown on the drawings. The 100 cycle energy supplied for the operation of the coded track circuits in the cab signal equipment on trains moving through the stretch is supplied from a suitable source of alternating current energy, not shown, but having terminals designated by the reference characters BX and NX, and it is to be understood that such energy may be furnished through the medium of a suitable transmission line extending along the stretch of track.

The contacts of relays which are recurrently operated are designated by dotted lines showing the alternative positions of the contacts, and the contacts of relays which are slow in operating are designated by arrows therethrough pointing in the direction in which the relay is slow to operate, i. e., downwardly for slow releasing relays and upwardly for slow pickup relays.

It is believed that a better understanding of my invention may be had by a detailed analysis of the operation of the arrangement shown in the drawings under various traffic conditions. The operation of the apparatus shown in Figs. 1A and 1B will be described first.

The apparatus is shown in the condition which it assumes when traffic conditions in advance of signal 4S are such that the signal control relays 4HR and 4DR at signal location 4S, Fig. 1B, are released. With relay 4HR released, an obvious circuit including back contact c of relay 4HR supplies energy to the red lamp R of signal 4S so that this signal displays a stop aspect.

For the purposes of a preliminary general description, it will be assumed that reverse code impulses generated by the apparatus at the code change point location are being supplied to the track rails 3 and 5 of section 2AT at this time at the entrance end thereof, and are being supplied to the winding of relay 4AR through the 100 cycle filter, during each released period of the code transmitting relay 4CTM, the back contact b of relay 4CTM closing the circuit for energizing relay 4AR. The recurrent operation of the contacts of relay 4AR causes energy to be supplied to the winding of relay 4AM, since each time that contact a of relay 4AR is picked up, energy is supplied by an obvious circuit to the capacitor Q2 through the limiting resistor 42, and when contact a of relay 4AR is released, the energy stored in capacitor Q2 is supplied through the winding of relay 4AM. Relay 4AM is selected and arranged in such manner that its release period is longer than the longest "off" time of the reverse code impulses which operate relay 4AR, so that the contacts of relay 4AM remain picked up during the intervals in which no energy is being supplied to its winding. With contact a of relay 4AM picked up, a circuit is established for supplying energy from the 75 code transmitter to the winding of relay 4CTM each time that contact b of relay 4AR is released. This circuit may be traced from terminal B at front contact a of the code transmitter 75CT, over front contact a of relay 4AM, back contact b of relay 4AR, back contact a of relay 4HR, and through the winding of relay 4CTM to terminal N. As previously pointed out, the impulses of reverse code energy are of very short duration, and occur at a rate much lower than the 75 code rate, so that during the intervals which the impulses of energy are not received, contact b of relay 4AR will be released to complete the circuit traced above, so that the winding of relay 4CTM

is energized by energy supplied over the contacts of code transmitter 75CT. The recurrent operation of contact a of relay 4CTM causes the recurrent supply of energy from the alternating current source designated by the reference characters BX and NX to the primary winding of the track transformer 2ATT. These impulses of master code energy, governed by the operation of relay 4CTM, are supplied to the rails 3 and 5 of section 2AT, through the 100 cycle filter, which presents only a low impedance to the 100 cycle energy, so that the larger portion of the energy is supplied to the track rails of the section in the usual manner.

The impulses of master code energy supplied from the exit end of section 2AT at the 75 code rate flow over the section rails to the code change point location shown in Fig. 1A, and through the secondary winding of transformer 2AITT and the 100 cycle filter to the winding of relay 2ATR. The circuit for energizing relay 2ATR is governed by a back contact b of the impulse relay 2AIR in multiple with the front contact of relay 2ATR. It will be assumed for the purposes of this preliminary discussion that contact b of relay 2AIR is released at the time that the 75 code impulse of master code energy is supplied to the rails of the section and, accordingly, energy is supplied through the 100 cycle filter to the winding of relay 2ATR. When contact a of relay 2ATR picks up, it establishes a stick circuit for itself to insure that energy will continue to be supplied to the winding of the relay, even in the event that contact b of relay 2AIR subsequently picks up before the impulse of master code energy is interrupted. The recurrent supply of impulses of energy to the winding of relay 2ATR causes its contacts to be operated at the corresponding code rate of 75 times per minute, so that relay 2ABSA is recurrently energized by a circuit including back contact d of relay 2ATR. The relay 2ABSA is selected and arranged so that its contacts are slower in releasing than the maximum picked-up time of relay 2ATR, so that as a result relay 2ABSA will be picked up as long as relay 2ATR is being supplied with coded energy at either one of the two code rates. With contact a of relay 2ABSA picked up, each time that contact c of relay 2ATR picks up, a circuit is established for supplying energy to the primary winding of transformer 2TT, which circuit includes front contact c of relay 2ATR, front contact a of relay 2ABSA, and the primary winding of transformer 2TT. Accordingly, impulses of energy coded at the 75 code rate will be supplied to the rails of section 2T at the exit end thereof and will flow over the section rails to the entrance end through the 100 cycle filter to operate the contacts of relay 2TR. The recurrent operation of contact a of relay 2TR causes the supply of energy to the top and bottom sections of the primary winding of decoding transformer 2DT with the consequent induction of alternating current energy having a frequency the same as the operation of the contacts of relay 2TR in the secondary winding of the decoding transformer. This alternating current energy is mechanically rectified by the simultaneous and synchronous operation of contact b of relay 2TR, and is supplied to the winding of the signal control relay 2HR. This results in the energization of relay 2HR, which has its contacts picked up as long as the track relay 2TR is following code at either one of the two master code rates. Energy is also supplied from the autotransformer portion of the decoding transformer 2DT to the decoding unit 180DU, to supply energy to the winding of relay 2DR. The parts are arranged in the manner well known in the art so that sufficient energy to pick up the contacts of relay 2DR is supplied to the winding of the relay when and only when the contacts of relay 2DR are operating at the 180 code rate, and at other times, the contacts of relay 2DR are released. Accordingly, it will be seen that, at this time contact a of relay 2DR is released and contact b of relay

2HR is picked up, thereby establishing an obvious circuit for supplying energy to the yellow lamp **Y** of signal **2S**, so that signal **2S** displays an approach aspect.

When signal **4S**, Fig. 1B, is displaying a yellow or an approach aspect, as determined by the energized condition of relay **4HR** and the energized or deenergized condition of relay **4DR** in accordance with traffic conditions in advance of signal **4S**, contact **a** of relay **4HR** will be picked up to connect the winding of relay **4CTM** to the circuit including front contact **a** of code transmitter **180CT**, so that the contacts of relay **4CTM** are operated at the 180 code rate at this time. Accordingly, the supply of energy to track section **2AT** at the exit end thereof is coded at the 180 code rate, causing the corresponding rate of operation of relay **2ATR** at the code change point location, Fig. 1A. The recurrent operation of contact **c** of relay **2ATR** at the 180 code rate will cause a supply of impulses of alternating current energy at the same rate to the rails of section **2T** at the exit end thereof, and as a result, relay **2TR** at the entering end of section **2T** will operate its contacts at the 180 code rate, so that the contacts of both relays **2HR** and **2DR** will be picked up, thereby establishing a circuit for supplying energy to the green lamp **G** of signal **2S**. If the supply of 100 cycle energy to the filter and thence to the winding of relay **2TR** at the entrance end of section **2T** is cut off for any reason, such as by the occupancy of section **2T** or section **2AT** by a train, the contacts of relay **2TR** and **2DR** will cease operating, with the result that relays **2HR** and **2DR** will release, the contact **b** of relay **2HR** establishing a circuit for supplying energy to the red lamp **R** of signal **2S**, so that the signal thereby displays a stop aspect.

As previously pointed out, when signal **4S** is displaying a red or stop aspect, signal **2S** will display a yellow or approach aspect, and the energy supplied to the rails of sections **2T** and **2AT** will be coded at the 75 code rate. If a train moving from left to right passes signal **2S**, the shunting effect of the wheels and axles of the train will cut off the supply of energy to the winding of relay **2TR**, so that relays **2HR** and **2DR** will be released with the consequence that signal **2S** will display a stop aspect behind the train. The impulses of energy at the 75 code rate supplied at the exit end of section **2T** will cause the cab signal apparatus on the train to display a yellow or approach aspect on the cab signal. As the train moves into section **2AT**, the supply of impulses of reverse code energy from the entering end of section **2AT** at the code change point location to the exit end of section **2AT**, Fig. 1B, will be cut off. Accordingly, the winding of approach relay **4AR** will no longer be energized by the impulses of reverse code energy during periodic "off" intervals of the master code energy supplied at that end of the section, and contacts **a** and **b** of relay **4AR** will release and remain released. After a short time interval, the contact **a** of relay **4AM** will release, since energy is no longer being recurrently supplied to the winding of this relay over contact **a** of relay **4AR**, and the opening of front contact **a** of relay **4AM** will interrupt the circuit for supplying energy to the winding of the code transmitting relay **4CTM**. With relay **4CTM** deenergized, the supply of impulses of 75 code to the rails of section **2AT** will be interrupted so that the cab signal apparatus on the approaching train will change the aspect displayed by the cab signal from approach to restricting, thereby indicating to the engineman that he is approaching a stop signal.

If it is then assumed that the traffic conditions in advance of signal **4S** become such that signal **4S** changes its aspect from stop to approach or clear, the train in section **2AT** will then have the aspect of the cab signal thereon changed, since relay **4HR** will be picked up upon the clearing of signal **4S**, so that the winding of code transmitter **4CTM** will be connected to the source of energy over contact **a** of the code transmitter **180CT**, with the result that 100 cycle energy coded at the rate of 75

180 times per minute will be supplied to the rails of section **2AT** and thereby operate the cab signal apparatus on the train in section **2AT** to provide a clear aspect.

When the train in question passes signal **4S** and enters section **4T**, relay **4HR** will be released, and its contact **a** will interrupt the circuit for supplying energy to the winding of the code transmitting relay **4CTM**, so that the supply of 100 cycle energy to the rails of section **2AT** will again be cut off.

10 While the train is occupying section **2AT**, impulses of reverse or feed-back code energy are supplied from the code change point location by the operation of the equipment in a manner to be subsequently described. These impulses of reverse code energy are supplied over the rails of section **2AT** behind the train as it proceeds 15 through section **2AT**, and when the rear of the train vacates this section, these impulses will cause the recurrent operation of relay **4AR**, so that the code detecting relay **4AM** will again be energized. With relay **4AM** energized, the circuit previously traced for energizing relay **4CTM** over front contact **a** of the code transmitter **75CT** is again established, and impulses of master code energy are accordingly transmitted from the exit end of section **2AT** to the entrance end thereof. Relay **2ATR** 20 is accordingly operated at the corresponding rate, to thereby cause the supply of coded energy at the 75 code rate to the exit end of section **2T**, which energy feeds over the section rails to the entrance end of this section, and causes operation of the contacts of relay **2TR** at the 25 75 code rate. As a result, relay **2HR** will be picked up, and with relay **2DR** released, the circuit for supplying energy to the yellow lamp **Y** of signal **2S** is again established.

30 If the signal **4S** is displaying a yellow or green aspect, the energy supplied to the sections **2AT** and **2T** will be coded at the 180 code rate, so that signal **2S** will display its clear or green aspect, and if a train enters section **2T** at this time, the cab signal apparatus on the train will be energized by impulses of energy at the 180 code rate so that the cab signal will display a clear aspect. When the train enters section **2AT**, the reverse code impulses supplied from the code change point location and fed over the section rails toward the exit end of the section will be shunted by the train, but this will have no effect 35 on the transmission of master code from the exit end of the section, since contact **a** of relay **4HR** will be picked up to thereby govern the operation of the code transmitting relay **4CTM** directly over contact **a** of the code transmitter **180CT**. Although relay **4AR** will cease its 40 operation upon the entrance of the train in section **2AT**, due to the shunting of the reverse code impulses, relay **4AM** will remain picked up at this time, since an auxiliary energizing circuit is closed over front contact **b** of relay **4HR**. This auxiliary energizing circuit is provided 45 to maintain the relay **4AM** energized under the condition 50 in which signal **4S** has its aspect changed from clear or approach to stop, in which case a lapse of time occurs 55 to maintain the relay **4AM** energized under the condition in which signal **4S** has its aspect changed from clear or approach to stop, in which case a lapse of time occurs 60 before the reverse code impulses supplied to relay **4AR** are effective to energize the relay **4AM**.

Having thus described in a general manner the mode of operation of the coded railway signaling system shown in the drawings, I will now describe in detail the operation of the apparatus at the code change point location which is effective to generate impulses of reverse code energy 65 for energizing the approach relay at the exit end of section **2AT**.

As previously pointed out, the pickup circuit for relay **2ATR** includes a back contact **b** of the impulse relay **2AIR**, and a stick circuit is provided for relay **2ATR** including front contact **a** of relay **2ATR**, so that the release of the impulse relay **2AIR** is checked over its back contact **b** before relay **2ATR** can be picked up, but, thereafter, relay **2ATR** will remain picked up for the duration of a master code impulse, by virtue of the stick circuit established over its own front contact **a**. The

transformer 2AITT has its primary winding controlled by a circuit including contact *b* of relay 2ATR and contact *a* of relay 2AIR. As will be seen from the drawings, the primary winding of transformer 2AITT is short-circuited when contact *a* of relay 2AIR is released, or when contact *b* of relay 2ATR is picked up. Under either of these circumstances, the primary winding of transformer 2AITT is short-circuited in order to provide a low impedance path through the secondary winding for supplying energy to the winding of relay 2ATR. Energy is supplied from the alternating current source to the primary winding of transformer 2AITT during the time that contact *b* of relay 2ATR is released and contact *a* of relay 2AIR is picked up. Accordingly, it will be seen that if relay 2AIR is picked up at the time that contact *b* of relay 2ATR releases, energy will be supplied to the rails of section 2AT through the transformer 2AITT, to thereby supply an impulse of reverse code energy to the apparatus at the exit end of section 2AT.

The first impulse relay 2AIR and the second impulse relay 2AIM are controlled in such manner that these relays operate in a predetermined cycle to result in the periodic operation of relay 2AIR to produce code impulses having a relatively short "on" time and a relatively long "off" time, with the relays being governed by the action of track relay 2ATR in such manner that at times relays 2AIR and 2AIM function as a pulse generating circuit which can operate independently of the operation of relay 2ATR, and at other times operate as a pulse generating circuit which is synchronized with the operation of relay 2ATR.

Considering the first instance, let it be assumed that no impulse of master code energy are being supplied through the secondary winding of transformer 2ATT and the 100 cycle filter to the winding of relay 2ATR, which condition may be the result of a train occupying section 2AT. Under these conditions, it will be remembered that the apparatus at the code change point location continues to generate impulses of reverse code energy, so that when the train vacates section 2AT, the reverse code impulses will cause the operation of the approach relay 4AR and the subsequent energization of the detector relay 4AM at the exit end of section 2AT, to thereby restore the master code energy governed by the 75 code transmitter at that location. Under such circumstances, at the code change point location, relay 2ATR will have its contacts continuously released. Accordingly, no energy will be supplied to the winding of relay 2ATM, since the circuit for energizing this relay is open at front contact *d* of relay 2ATR. With relay 2ATM deenergized, the circuit for supplying recurrent impulses of energy to the winding of relay 2AFSA will be interrupted at front contact *a* of relay 2ATM, so that relay 2AFSA will also be released at this time.

Assuming that contact *c* of relay 2AIR is released, energy is supplied by an obvious circuit to the winding of relay 2AIM. Relay 2AIM is a relay characterized by being relatively slow in picking up its contacts after its winding has been energized. Accordingly, after a predetermined time interval following the release of the contacts of relay 2AIR, the contacts of relay 2AIM will pick up. When contact *a* of relay 2AIM picks up, energy is supplied to the winding of relay 2AIR over a circuit including back contact *a* of relay 2AFSA and the winding of relay 2AIR to terminal N. Additionally, the capacitor Q1 is charged through the resistor R1. When relay 2AIR picks up, the circuit for supplying energy to relay 2AIM is interrupted at back contact *c* of relay 2AIR, and relay 2AIM thereafter releases. The release of contact *a* of relay 2AIM interrupts the circuit for energizing relay 2AIR, but the energy stored in the capacitor Q1 is then supplied over back contact *a* of relay 2AFSA and through the winding of relay 2AIR, so that relay 2AIR is maintained in its energized condition for a short

time interval. After the expiration of this time interval, relay 2AIR will release, and its back contact *c* will again close the energizing circuit for relay 2AIM, whereupon relay 2AIM again picks up, reenergizing relay 2AIR. It will be seen, therefore, that at this time, with relay 2ATR continuously deenergized, the relays 2AIR and 2AIM will successively pick up and release. The relays are selected and arranged and the capacitor Q1 and resistor R1 are proportioned so that the cycle of operation of relay 2AIR is represented by a relatively short time in which the contacts of relay 2AIR are picked up, followed by a relatively long interval during which the contacts of relay 2AIR are released. These time intervals may be, for example, of the order of 0.08 second to 0.130 second for the "on" or picked-up time of relay 2AIR, and an "off" or released time for relay 2AIR of the order of 1.5 seconds.

With contact *b* of relay 2ATR released, energy is supplied to the primary winding of transformer 2AITT each time that contact *a* of relay 2AIR picks up, with the result that impulses of energy having a relatively short "on" time and a relatively long "off" time are supplied to the rails of section 2AT.

When section 2AT is unoccupied, the impulses of reverse code energy supplied from the apparatus at the code change point location operate the code following approach relay 4AR at the exit end of section 2AT, the cycle of operation of this relay following that of the reverse code energy in that its contacts are released for a relatively long period and picked up for a relatively short period. If the signal 4S is at stop, so that back contact *a* of relay 4HR is closed, the code transmitting relay 4CTM is operated recurrently at the 75 code rate during the long "off" periods of the reverse code energy in which contact *b* of relay 4AR is released to complete the circuit for governing relay 4CTM. When an impulse of reverse code energy picks up relay 4AR during the released time of contact *b* of relay 4CTM, the circuit for governing relay 4CTM is momentarily opened at back contact *b* of relay 4AR, and when the impulse of reverse code energy ceases, contact *b* of relay 4AR is again closed, so that relay 4CTM can again operate to code the supply of energy from transformer 2ATT to the section rails. Accordingly, it will be seen that, during the unoccupied condition of section 2AT with signal 4S at stop, the master code energy supplied from the exit end of the section to the entrance end of the section consists of master code impulses at the 75 code rate, interspersed at intervals by an impulse of reverse code energy.

The operation of relays 2AIR and 2AIM under the condition in which track relay 2ATR is operating in response to impulses of master code energy supplied from the exit end of section 2AT is substantially similar to the operation of the relays when the track relay 2ATR is continuously released. However, as previously pointed out, the operation of the impulse generating relays may be synchronized with the operation of the track relay 2ATR, so that the reverse code impulses are transmitted at the proper time and so that there is no interference with the reception of the master code impulses. With relay 2ATR operating its contacts, relay 2AFSA will be picked up, and relay 2AIR is then governed by a pickup circuit which includes front contact *a* of relay 2AFSA, back contact *b* of relay 2ATM, front contact *b* of relay 2AIM, and front contact *d* of track relay 2ATR. A stick circuit is provided for relay 2AIR including front contact *c* of relay 2AIR, front contact *b* of relay 2ATM, and front contact *a* of relay 2AFSA. It will be seen that relay 2AIR cannot pick up immediately if relay 2AIM picks up during the time that the track relay 2ATR is picked up because the pickup circuit for relay 2AIR is interrupted at back contact *b* of relay 2ATM, which will be picked up while the contacts of relay 2ATR are picked up. In this manner, the energization of relay 2AIR cannot take place during the very short

interval when the contact *d* of relay 2ATR happens to pick up after contact *b* of relay 2AIM picks up, so that insurance is provided that relay 2AIR will always be picked up for a minimum time interval which is sufficiently long to insure the proper operation of the apparatus to transmit a reverse code pulse of sufficient duration to properly operate the apparatus at the exit end of section 2AT.

However, on the next pickup of relay 2ATR, relay 2AIM will still be picked up, and a pickup circuit will be established over front contact *d* of relay 2ATR, front contact *b* of relay 2AIM, back contact *b* of relay 2ATM, front contact *a* of relay 2AFSA, and through the winding of relay 2AIR to terminal N. The relays are selected and designed so that the time required for relay 2AIR to pick up following the pickup of relay 2ATR is much less than the time required for relay 2ATM to pick up. Accordingly, relay 2AIR will pick up, followed by the picking up of relay 2ATM. When contact *b* of relay 2ATM picks up, it interrupts the pickup circuit just traced for relay 2AIR, but establishes the stick circuit for the relay which includes front contact *b* of relay 2ATM and front contact *c* of relay 2AIR. Accordingly, relay 2AIR will remain picked up until relay 2ATM releases following the release of contact *b* of relay 2ATR. As pointed out hereinbefore, the release of contact *b* of relay 2ATR, with contact *a* of relay 2AIR picked up, will result in energy being supplied to the winding of transformer 2ATT, so that an impulse of reverse code energy is supplied to the rails of section 2AT. Shortly thereafter, relay 2AIR will release, and its contact *c* will interrupt the stick circuit for relay 2AIR and reestablish the energizing circuit for relay 2AIM, which after a relatively long time interval will pick up its contacts, so that the cycle described above will be repeated.

The apparatus is constructed and arranged in such manner, and the operating times of the various relays are so chosen, that the apparatus functions to transmit a pulse of reverse code energy during at least every second or third cycle of the master code energy impulses. The frequency at which the impulses of reverse code energy are transmitted from the entrance end of section 2AT is sufficiently low that the cab signal apparatus on a train which may under certain circumstances be moving through the section in the direction opposite to that of normal traffic, namely, from right to left rather than from left to right, will not be affected, since the frequency at which the impulses would be received by this equipment is too low to cause operation of the cab signal apparatus.

As previously pointed out, the relay 4AM, Fig. 1B, is energized as a result of the recurrent operation of contact *a* of relay 4AR when reverse code energy is being received at the exit end of section 2AT. An auxiliary energizing circuit governed by front contact *b* of relay 4HR also supplies energy to the winding of relay 4AM as long as relay 4HR is picked up, so that signal 4S is displaying a yellow or green aspect. When signal 4S changes its aspect to stop by the release of relay 4HR, the intervening interval in which the contacts of relay 4AR will not be operating might be sufficiently long to cause relay 4AM to release, with the result that its contact *a* would interrupt the circuit for governing the code transmitting relay 4CTM. Accordingly, the auxiliary energizing circuit will provide energy to charge the capacitor Q2, so that at the time that relay 4HR releases, with contact *a* of relay 4AR released, relay 4AM will remain in its picked-up position for a sufficiently long time interval to permit the initiation of the transmission of reverse code impulses from the entrance end of section 2AT, to thereby maintain relay 4AM picked up.

Referring now to Fig. 2, there is shown a fragmentary diagram illustrating the apparatus employed at the code change point location in a second embodiment of my invention, which employs one less relay than the arrangement shown in Fig. 1A. The principal difference be-

tween the apparatus shown in Fig. 2 and the apparatus shown at the code change point location of Fig. 1A lies in the fact that the apparatus shown in Fig. 2 is arranged so that the impulse relay 2AIR is energized to cause the transmission of an impulse of reverse code energy after the track relay 2ATR has been released for an interval sufficiently long to allow the reverse code impulse relay to pick up. In other words, the impulses of reverse code energy are delayed in their transmission by the amount of time required for the impulse relay 2AIR to pick up after the release of the track relay 2ATR, whereas in Fig. 1A, the impulse of reverse code energy was transmitted immediately upon the release of the contacts of the track relay 2ATR, since the reverse code impulse relay 2AIR was picked up prior to the release of the track relay 2ATR.

With the arrangement shown in Fig. 2, the track repeater relay 2ATM is not required, but the arrangement shown in Fig. 2 is limited to operation with track circuits in which the parameters are such that the increase in time required for the transmission of the reverse code impulse will not limit the proper operation of the apparatus.

In describing the operation of the apparatus shown in Fig. 2, it will first be assumed that no code energy is being received from the exit end of section 2AT, and that the apparatus at the code change point location is functioning to generate impulses of reverse code energy having a duration and repetition frequency determined by the constants of the relays and associated apparatus.

With the contacts of relay 2ATR continuously released, relay 2AFSA will be released, since no energy is supplied thereto by the circuit including front contact *b* of relay 2ATR. With relay 2AIR released, an energizing circuit for the slow pickup relay 2AIM is established over back contact *c* of relay 2AIR, and after a time interval determined by the pickup characteristics of relay 2AIM, this relay will pick up its contacts. When contact *a* of relay 2AIM closes, a shunt circuit around the winding of relay 2AIM is established, including the current limiting resistor R4. It will be apparent that this circuit has no effect upon the pickup time of relay 2AIM, but does serve to provide a snubbing circuit for delaying the release of relay 2AIM.

When contact *c* of relay 2AIM picks up, a circuit is established for supplying energy to the winding of relay 2AIR, which circuit may be traced from terminal B at back contact *a* of relay 2AFSA, over back contact *c* of track relay 2ATR, front contact *c* of relay 2AIM, and through the winding of relay 2AIR to terminal N. When relay 2AIR picks up, its front contact *a* establishes an obvious circuit for supplying 100 cycle energy to the primary winding of the impulse transformer 2ATT, so that the track section 2AT is supplied with 100 cycle energy at the entrance end thereof. When contact *c* of relay 2AIR picks up, the circuit for energizing relay 2AIM is interrupted and after a short time interval the contacts of relay 2AIM will release. The opening of front contact *c* of relay 2AIM interrupts the previously traced circuit for energizing relay 2AIR, but this relay is slightly slow in releasing, and its contacts will remain picked up until the contacts of relay 2AIM have closed their back contacts. When back contact *c* of relay 2AIM closes, the winding of relay 2AIR is directly shunted thereby, further delaying the release of relay 2AIR.

When relay 2AIR finally releases its contacts, its contact *a* interrupts the circuit for supplying energy to the winding of transformer 2ATT, thereby terminating the impulse of reverse code energy, and its back contact *c* reestablishes the circuit for energizing the winding of relay 2AIM, so that the cycle described above is repeated. The circuit components and the relays are constructed and arranged in such manner that the impulses of reverse code energy are supplied with a relatively short

"on" time and a relatively long "off" time as previously described in connection with Fig. 1A.

Under the condition in which master code energy is being received at the entrance end of section 2ATR, causing the code following operation of track relay 2ATR, the apparatus for generating the reverse code impulses, must of course, be properly synchronized so that the impulses of reverse code energy are transmitted at the proper times so as not to interfere with the reception of the master code impulses. This operation is different under different circumstances, depending upon the operation of the track relay 2ATR, and, accordingly, the detailed operation of the apparatus under these different conditions will now be described.

If relay 2AIM picks up its contacts during the time that track relay 2ATR is released, it is necessary to prevent the picking up of relay 2AIR until after the next "on" period of relay 2ATR, that is, the next time in which the contacts of relay 2ATR are picked up. This is necessary since if relay 2AIM picked up just before the termination of the "off" period of the master code impulse, and relay 2AIR picked up to transmit a reverse pulse, the succeeding pulse of master code energy would be interfered with by the pulse of reverse code energy, thus causing a condition of scrambled code in the track circuit. Referring to the drawing, it will be seen that at this time with the contacts of relay 2ATR in continuous operation, energy will be recurrently supplied to the winding of relay 2AFSA each time that contact *b* of relay 2ATR is picked up. Since relay 2AFSA is sufficiently slow in releasing to bridge the periods in which contact *b* of relay 2ATR is released, relay 2AFSA will be picked up at this time. A charging circuit for capacitor Q3 is established each time that contact *c* of relay 2ATR is picked up, provided that contact *b* of relay 2AIM is also picked up. This circuit may be traced from terminal B at front contact *c* of relay 2ATR, over front contact *a* of relay 2AFSA, front contact *b* of relay 2AIM, and through the current limiting resistor R3 to the capacitor Q3, the other side of the capacitor being connected to terminal N. When contact *b* of relay 2AIM is released, it establishes an obvious short-circuiting circuit for the capacitor Q3, so that the capacitor Q3 will be discharged when relay 2AIM is released. The energy stored by capacitor Q3 can be supplied to the winding of the impulse relay 2AIR by a circuit which includes the limiting resistor R3, front contact *b* of relay 2AIM, front contact *a* of relay 2AFSA, back contact *c* of relay 2ATR, and front contact *c* of relay 2AIM. It can thus be seen that if relay 2AIM picks up with relay 2ATR released, no charging energy will be supplied to the impulse relay 2AIR upon the subsequent release of the track relay 2ATR, since it is necessary that contact *c* of relay 2ATR be picked up at the time relay 2AIM is picked up in order to supply energy to the capacitor Q3, and thus if relay 2AIM was not picked up during the previous picked-up time of relay 2ATR, no energy will be stored in the capacitor Q3. However, during the next picked-up interval of relay 2ATR, with relay 2AIM picked up, energy will be supplied to the capacitor Q3, and when relay 2ATR releases, the circuit previously traced will be established for supplying energy from the capacitor Q3 to the winding of relay 2AIR, with the result that relay 2AIR will pick up to thereby cause the transmission of an impulse of reverse code energy. The picking up of contact *c* of relay 2AIR will interrupt the circuit for supplying energy to the winding of relay 2AIM, but the snubbing circuit including the resistor R4 is connected across the winding of relay 2AIM at this time by front contact *a* of relay 2AIM, so that the relay is slowed in its release. When relay 2AIM does release, the capacitor Q3 is short-circuited through the resistor R3, and additionally, a short circuit is established across the winding of relay 2AIR by back contact *c* of relay 2AIM so that relay

2AIR is slowed in its releasing for a sufficient time interval to cause the transmission of proper length of reverse code impulse.

If relay 2AIM picks up while relay 2ATR is picked up, the circuit for supplying energy from the low voltage source to the capacitor Q3 will be established and when contact *c* of relay 2ATR releases, relay 2AIR will be picked up by the circuit previously traced, to thereby transmit an impulse of reverse code energy. The principal purpose of the resistance snub R4 which is connected across the winding of relay 2AIM when contact *a* of this relay is picked up is to provide a sufficient release interval on relay 2AIM so that in the event relay 2AIM picks up just before relay 2ATR releases, the capacitor Q3 will supply sufficient energy through the circuit including front contact *b* of relay 2AIM to insure that relay 2AIR will pick up for a sufficient time interval to send an impulse of reverse code energy of proper length. If the capacitor Q3 has been insufficiently charged due to the fact that relay 2AIM picked up just momentarily before contact *c* of relay 2ATR released, capacitor Q3 will not be supplied with sufficient energy to pick up relay 2AIR fully and keep this relay picked up for a sufficient time duration for sending the reverse code impulse. However, if relay 2AIR is energized sufficiently to cause contact *c* of relay 2AIR to just open, it will be seen that the energizing circuit for relay 2AIM is opened. If the resistance snub for relay 2AIM were not provided, this relay would release, thus requiring relay 2AIM to pick up again before an impulse of reverse code energy could be transmitted. However, with the resistance snub on relay 2AIM, the release of this relay is delayed by a sufficient time interval so that, upon the next energization of relay 2ATR, capacitor Q3 will be fully charged, and when contact *c* of relay 2ATR releases, the energy stored in capacitor Q3 will be supplied to the winding of relay 2AIR to thereby pick up this relay and cause the transmission of an impulse of reverse code energy of proper length.

It can be seen from the foregoing that my invention provides a number of useful advantages in that it uses apparatus which is conventional in the railway signaling art, provides the necessary functions for a code change point without the use of line wires, and is noninterfering with the normal operation of the coded track circuit apparatus, so that it may be employed with existing coded railway signaling systems with a minimum of changes in the existing apparatus.

Although I have herein shown and described only two forms of coded railway signaling systems embodying my invention, it is to be understood that various changes and modifications may be made therein within the scope of the appended claims without departing from the spirit and scope of my invention.

Having thus described my invention, what I claim is:

1. In combination with a section of railway track through which trains normally move in a given direction, the trains traversing said section being equipped with cab signal apparatus responsive only to alternating current energy coded at one or another of a plurality of traffic code rates and being non-responsive to alternating current energy coded at a rate less than the lowest rate of said traffic code rates, the combination comprising supply means at the exit end of said section for at times supplying alternating current energy to the rails of said section at one or another of said traffic code rates in accordance with traffic conditions in advance of said section, means at the entrance end of said section for supplying reverse code impulses of alternating current energy to the rails of said section at a rate less than the lowest of said traffic code rates, and detector means at the exit end of said section responsive only to said reverse code impulses, said supply means being governed by said detector means to cut off the supply of alternating current energy at the exit end of

said section when said reverse code pulses are cut off and the section next in advance is occupied.

2. In combination with a section of railway track through which trains normally move in a given direction, the trains traversing said section being equipped with cab signal apparatus responsive only to alternating current energy coded at one or another of a plurality of traffic code rates and being nonresponsive to alternating current energy coded at a rate less than the lowest rate of said traffic code rates, the combination comprising supply means at the exit end of said section for at times supplying alternating current energy to the rails of said section at one or another of said traffic code rates in accordance with traffic conditions in advance of said section, reverse code generating means at the entrance end of said section for supplying reverse code impulses of alternating current energy to the rails of said section at a rate less than the lowest of said traffic code rates, means associated with said reverse code generating means for synchronizing the transmission of said reverse code impulses with the intervals between the impulses of traffic code energy received from the exit end of said section, detector means at the exit end of said section responsive only to said reverse code impulses, said supply means being governed by said detector means to cut off the supply of alternating current energy at the exit end of said section when said reverse code pulses are cut off and the section next in advance is occupied.

3. In combination with a section of railway track through which trains normally move in a given direction, the trains traversing said section being equipped with cab signal apparatus responsive only to alternating current energy coded at one or another of a plurality of different traffic code rates and being nonresponsive to alternating current energy coded at a rate less than the lowest of said traffic code rates, the combination comprising supply means at the exit end of said section for at times supplying alternating current energy to the rails of said section at one or another of said traffic code rates in accordance with traffic conditions in advance of said section, code following track relay means located at the entrance end of said section and responsive to alternating current energy supplied thereto over the rails of said section from the exit end of the section, reverse code generating means at the entrance end of said section for supplying reverse code impulses of alternating current energy to the rails of said section at a rate less than the lowest of said traffic code rates, said reverse code generating means including a first and a second impulse relay, said impulse relays alternately governing energization of each other to operate in a cyclic manner, means including a contact of said code following track relay for synchronizing the operation of said impulse relays with the reception of code pulses received from the exit end of said section, detector means at the exit end of said section responsive only to said reverse code impulses, said supply means being governed by said detector means to cut off the supply of alternating current energy at the exit end of said section when said reverse code pulses are cut off and the section next in advance is occupied.

4. In a coded signaling system having a code following relay operated at times by impulses of coded energy supplied thereto over a pair of conductors and having a code detecting relay which has its contacts picked up only when said code following relay is recurrently operating its contacts, reverse code generating means for supplying impulses of reverse code energy to said conductors during intervals spaced substantially longer than the intervals between impulses of coded energy received over said conductors, comprising a first impulse relay and a second impulse relay, said second impulse relay having contacts which are relatively slowing in picking up after the relay is energized, first circuit means governed by said first impulse relay for energizing said second impulse relay when said first impulse relay is released, second circuit means governed by said second impulse relay for energizing said

first impulse relay when said second impulse relay is picked up and said code detecting relay is released and for energizing said first impulse relay when said second impulse relay is picked up, said code following relay is released, and said code detecting relay is picked up, and means for maintaining said first impulse relay energized for applying a reverse code pulse to said pair of conductors only when said code detecting relay is de-energized.

5. In a coded railway signaling system, in combination, a code following track relay having contacts which are recurrently operated at times by energy supplied thereto over the rails of a track section, a code following repeater relay governed by a contact of said code following track relay, a front contact repeater relay governed by said code following repeater relay and having contacts which are picked up when said code following track relay is recurrently operating its contacts, a first impulse relay, a second impulse relay having contacts which are relatively slow in picking up after the relay is energized, a circuit for energizing said second impulse relay including a back contact of said first impulse relay, a first pickup circuit for said first impulse relay including a front contact of said front contact repeater relay, a back contact of said code following repeater relay, a front contact of said second impulse relay and a front contact of said code following track relay, a second pickup circuit for said first impulse relay including a back contact of said front contact repeater relay and a front contact of said second impulse relay, a stick circuit for said first impulse relay including a front contact of said front contact repeater relay, a front contact of said code following repeater relay and a front contact of said first impulse relay, and circuit means governed by a back contact of said code following track relay and a front contact of said first impulse relay for supplying energy to the rails of said track section.

6. In a coded railway signaling system, in combination, a code following track relay having contacts which are recurrently operated at times by energy supplied thereto over the rails of a track section, a code following repeater relay governed by a front contact of said code following track relay, a front contact repeater relay governed by said code following repeater relay and having contacts which are picked up when said code following track relay is recurrently operating its contacts, a first impulse relay, a second impulse relay having contacts which are relatively slow in picking up after the relay is energized, a circuit for energizing said second impulse relay including a back contact of said first impulse relay, a first pickup circuit for said first impulse relay including a front contact of said front contact repeater relay, a back contact of said second impulse relay and a front contact of said code following track relay, a second pickup circuit for said first impulse relay including a back contact of said front contact repeater relay and a front contact of said second impulse relay, a stick circuit for said first impulse relay including a front contact of said front contact repeater relay, a front contact of said code following repeater relay, a back contact of said second impulse relay and a front contact of said code following track relay, a second pickup circuit for said first impulse relay including a back contact of said front contact repeater relay and a front contact of said first impulse relay; means governed by said first impulse relay for disconnecting said code following track relay from the rails of said section when said first impulse relay is picked up and said code following relay is de-energized, and circuit means governed by a back contact of said code following track relay and a front contact of said first impulse relay for supplying energy to the rails of said track section only when said code following track relay is de-energized.

7. In a coded railway signaling system, in combination, a code following track relay having contacts which are recurrently operated at times by energy supplied thereto over the rails of a track section, a front contact repeater relay governed by said code following track relay and having contacts which are picked up when said code following track relay is recurrently operating its contacts, a first impulse relay, a capacitor, and a source of charging energy for said capacitor; a second impulse relay having

contacts which are relatively slow in picking up after the relay is energized, a circuit for energizing said second impulse relay including a back contact of said first impulse relay, a first pickup circuit for said first impulse relay including a front contact of said second impulse relay, a back contact of said front contact repeater relay and a back contact of said code following track relay, a second pickup circuit for said first impulse relay including a front contact of said second impulse relay, a back contact of said code following track relay, a front contact of said front contact repeater relay, and said capacitor; a circuit for supplying energy from said source to said capacitor including a front contact of said code following track relay and a front contact of said front contact repeater relay, and means governed by contacts of said first impulse relay for disconnecting said code following relay from the rails of said section when said code following relay is de-energized and for connecting a source of energy to the rails of said section when said first impulse relay is picked up.

8. In a coded signaling system having a code following relay operated at times by impulses of coded energy sup-

plied thereto over a pair of conductors, reverse code generating means for supplying impulses of reverse code energy to said pair of conductors when said code following track relay is de-energized, comprising a first and a second impulse relay, a first circuit means governed by said first impulse relay for energizing said second impulse relay when said first impulse relay is released, second circuit means governed by said second impulse relay for energizing said first impulse relay when said second impulse relay is picked up, holding means for maintaining said first impulse relay energized during an energized period of said code following track relay and until said code following track relay is de-energized, and means governed by a contact of said first impulse relay and a contact of said code following track relay for supplying energy to said pair of conductors.
